UNITED STATES PATENT OFFICE

GEBHARD C. BOHN, OF ST. PAUL, MINNESOTA

REFRIGERATOR FRAME

Application filed May 5, 1930. Serial No. 449,892.

The present invention relates to a refrigerator frame, and more particularly to knock-down type of refrigerator frames in which the parts thereof can be readily removed and reassembled.

In many of the larger refrigerators, such as those used in large residences, clubs, and commercial refrigerators, it is impossible to get the refrigerator in through the door or other opening available and it is necessary to disassemble the refrigerator to get it in the desired location. Various expedients have been resorted to in order to facilitate assembly and disassembly of a refrigerator, but in most cases it is necessary for one familiar with refrigerator construction to perform the operation of disassembling and re-assembling the refrigerator, and frequently requires the reshaping of some of the parts before the operation is completed. Furthermore, such assembly and disassembly frequently requires the removal of some of the insulating units incorporated therein. These units are frequently injured by such removal and replacement, thus reducing their efficiency.

An object of the present invention is to make a knock-down type of refrigerator which can be readily assembled and disassembled without the use of complicated tools and by an ordinary mechanic or layman.

Another object is to make an improved and simplified knock-down type of refrigerator.

In order to attain these objects, there is provided, in accordance with one form of the invention, a base member, having insulation therein and having metal sheathing interiorly and exteriorly thereof, and end members adapted to be mounted on said base to be supported thereon. These end members are adapted to supportingly engage a front and a rear member, and the assembled front, rear, and end members are arranged to receive a removable top member which in turn is adapted to receive a removable refrigerating unit.

These and other features of the invention will be more fully brought out in the following description and the accompanying drawings, wherein:

Figure 1 is a view in perspective of a refrigerator frame embodying the present invention.

Figure 2 is a view in top elevation of one of the end members thereof.

Figure 3 is a view in side elevation of the structure shown in Figure 2.

Figure 4 is a view in front elevation of the front member of said frame.

Figure 5 is a sectional view on the line 5—5 of Figure 4.

Figure 6 is a view in top elevation of the structure shown in Figure 4.

Figure 7 is a view in top elevation of a removable top member.

Figure 8 is a sectional view on the line 8—8 of Figure 7.

Figure 9 is a view in top elevation of a removable front strip for the structure shown in Figure 7.

Figure 10 is a view in side elevation of the structure shown in Figure 9.

Figure 11 is an end view of the structure shown in Figure 9.

Figure 12 is a view in front elevation of a rear frame member.

Figure 13 is a sectional view on the line 13—13 of Figure 12.

Figure 14 is a view in top elevation of a base member.

Figure 15 is a sectional view on the line 15—15 of Figure 14; and

Figure 16 is a sectional view on the line 16—16 of Figure 14.

Referring to the drawings in detail, a refrigerator framework A comprises the following co-ordinating units, base B, front C, rear D, ends E, top F, and removable rail for front of top G.

The base (see Figures 14, 15, and 16) comprises two end rails 1 and 2 and side rails 3 and 4, securely connected together in the form of a rectangular frame, as by means of mortise and tenon joints. The front rail 4 is somewhat narrower than the rear rail 3 of the base, and the end rails thereof are cut away as at 5 to receive inwardly projecting portions of the refrigerator front frame member. Wooden strips 6 and 7 are secured, one on each end of the base member,

to fit into and assist in supporting the end frame members. Wooden strips 8 and 9 are secured on the inner side of each of the side rails 3 and 4 to add rigidity to the base member.

The two end frame members E are constructed, as shown in Figures 2 and 3. These end frame members comprise vertical rails 10 and 11 with transverse rails 12 and 13 connected at the top and bottom thereof respectively. The bottom rail is narrower than the top rail and is set upwardly from the bottom of the vertical rails a distance equal to the width of the transverse strips 6 and 7 mounted on the ends of the base frame member. The bottom and top rails 12 and 13, and also a central transverse rail 14 are secured to the vertical rails by means of mortise and tenon joints, the tenons extending entirely through the vertical rails and projecting beyond the outer surfaces of said vertical rails. The forward side of the front vertical rail is notched out as at 15 to form a half lap joint with a front rail of the refrigerator top structure, while the top of the rear vertical rail is notched as at 16 to form an offset portion to assist in supporting a removable top structure. The lower ends of both the front and rear rails are notched as at 17 to fit over and rest upon the base structure to assist in supporting the end frame members. A board 18 is secured in position above the lower rail 13 and a similar board 19 is secured below the upper rail 12. These boards are of the same width as the vertical rails 10 and 11 and form, in conjunction with the side rails and the transverse center rail 14, rectangular frames for the reception of insulating material, not shown, with which refrigerators are customarily insulated.

The front frame member (see Figures 4, 5, and 6), comprises vertical side rails 20 and 21 and transverse top and bottom rails 22 and 23 securely connected together as by means of mortise and tenon joints to form a rigid rectangular frame. A vertical center post 24 is securely mounted in the frame thus formed, and transverse division members 25 and 26 are mounted as required to divide the front 50 into the required door openings. Around the interior of each of the door openings thus formed are secured wooden strip 27 which taper toward their forward edge, as shown in the sectional view of Figure 2. These strips 55 are undercut beneath both their front and rear edges to provide recesses for receiving the flanged edges of enameled sheathing plates, not shown, in accordance with a well known practice in the refrigerator art. The tapered 60 strips 27 are used to form the door opening so to correspond to the shape of the doors, not shown, which are to be inserted therein. The doors used may be of a conventional type commonly used with enamel sheathed refrigerators. Grooves such as 28 and 29 are pro-

vided in the outer surface of the front frame to receive the flanged edges of the enameled sheathing plates. Each of the vertical side rails is provided with three holes 30, 31, and 32, to receive tie bolts which extend entirely through the assembled framework from front to rear and tie the entire structure into a single solid unit. Mortises, not shown, are cut in the rear face of each of the vertical side rails of the front frame member to receive the 75 tenons 33 of the end frame members.

The rear frame member D, shown in Figures 12 and 13, comprises vertical side rails 34 and 35 and top and bottom rails 36 and 37 securely fastened together by mortise and tenon joints. A vertical center post 38 is securely fastened in position in this frame and lateral division members 39 and 40 are also secured in position to divide the rear frame member into rectangular compartments for 85 the reception of insulation. The center post 38 and the lateral division members 39 and 40 are of the thickness required for the insulation, but the side, top, and bottom rails are not, and for this reason boards 41 are secured 90 to the inner edges of these rails to build them out to the proper width. Mortises 42 are provided in the vertical rails 34 and 35 to receive the tenons of the end frame members. Openings 43, 44, and 45 are provided corresponding to the openings 30, 31, and 32 in the front frame members to receive the tie bolts 46 (see Figure 1).

The top structure comprises the frame F and the front rail G. The frame F comprises a rear rail 47 with similar, forwardly extending rectangular end portions at the ends thereof. These end portions comprise rail members 48 and 49, and a transversely positioned forward member 50 which forms with the other members a rectangular frame at each end for the reception of insulating material. Tenons 51 project forwardly from the rail members 49 to enter mortises 52 in the front rail G of the top structure. A refrigerator unit support strip 53 is securely fastened beneath the rails 47 and 49 to extend outwardly from these members into the rectangular bay formed by them. These support members are grooved on their lower sides to receive the flange of an enameled sheathing member, not shown.

The front rail member G comprises the member 54 notched out on its ends at 55 to seat in the notched-out portion of the front vertical rails of the end frame members 10 to form a half lap joint therewith. Mortises 56 are cut in the member 54 to receive the tenons 51. Holes 56 are drilled in the member 54 to receive screws by means of which this rail is secured to the end frame members 10 and an opening 57 is also provided, for the tie bolts 46. A refrigerator unit support strip 58 is also secured to the lower surface of the rail 130

54 to fit between the ends of the strips 53 to complete the rectangle.

To assemble the framework as shown in Figure 1, the base B is placed in position on a smooth level surface, the base being supported on legs 65 which are permanently attached thereto. The end members E are then placed in position on the base, the lower rails 13 resting on the strips 6 and 7 and the notched portions 17 resting on the end rails 1 and 2 of the base. The back frame member D is next placed in position, the tenons of the end frame members fitting into the mortises 42 of the rear frame member. The top frame member E is next placed in position, and is of a size to be readily insertable into the rectangular bay formed by the top rails 12 of the end frame members and the top rail 36 of the rear frame member. This top frame F rests upon and is supported by the boards 19 secured to the lower surfaces of the top rails 12 of the end frame members E, the top of the rear frame member center post 38, and also fits into the notched-out portion 15 of the rear rails of the end frame members. It is at this point of assembly that the refrigerating unit is placed in position, so that it may be moved into position in the rectangular bay in the top frame member F to rest on the strips 53.

30 The front rail assembly G of the top section is then placed in position and is secured in place by screws passing through the opening 56 and into the front vertical rails of the end frame members E.

35 The front frame member C is then placed in position with the tenons of the end frame members E entering the mortise in the front frame member and the tie bolts 46 are then inserted in the openings 30, 31, and 32, and 40 entirely through the framework from front to rear. Nuts 70 are then screwed onto the rear ends of the bolts and are drawn up tight to bind the entire framework into one solid unit.

45 The present specification is directed to the framework alone, since it would unnecessarily complicate the specification and drawings to show the remaining steps required to complete the refrigerator. However, it is apparent to one versed in the art that doors of a desired type may be mounted in the door openings in the front frame member, that insulation material will be placed in the 55 rectangular frames formed by the parts of the frame structure with the exception of the door openings, and the rectangular opening for the refrigerating unit in the top section, and that the frame members will be sheathed 60 inside and out with enameled metal sheathing members in a manner familiar to the art.

The assembly of the completed units will be accomplished in the same manner as that described for the assembly of the frame members.

I claim:

1. A knock-down refrigerator assembled from interlocking units, comprising a base, end members engaging said base and supported thereby, said end members having forwardly and rearwardly projecting elements to support front and rear members, a front and a rear member having recesses to receive the projections on the end members, a removable top portion insertable in the upper end of the enclosure formed by the front, rear, and end members, means carried by the top portion to removably support a mechanical refrigerating unit by horizontal insertion of the latter through the front of the frame and a removable rail mounted transversely across the forward portion of said top member.

2. A demountable refrigerator, comprising a base, end members engaging said base element to be supported thereby, a rear member having interlocking engagement with said end members, an offset seat spaced downwardly from the upper edge of said side and rear members, a removable top member supported on said seat and having a rectangular bay therein, open on the forward side thereof, a removable rail positioned across the forward side of said bay to enclose said bay, and a removable front portion having interlocking engagement with said end portions, means carried by the top portion to removably support a mechanical refrigerating unit by horizontal insertion of the latter through the front of the frame and tie means extending from front to rear of said structure to unite said structure into a single unit.

3. A refrigerator comprising a base, removable end members mounted thereon to be supported thereby, a rear member mounted transversely across the rear portion of said end members and having interlocking engagement therewith, a removable top member supported within the upper ends of said rear and end members, said top member having a rectangular bay therein open at the front, a rail across the front of said bay, and a front member having interlocking engagement with said end members, means carried by the top portion to removably support a mechanical refrigerating unit by horizontal insertion of the latter through the front of the frame and means connecting said front and rear members to said end members to unite said structure into a single unit.

4. A refrigerator, comprising a base having permanently connected supporting legs, an extension on each end of said base, a pair of end members mounted one on each end of said base to rest upon said extensions mounted on the ends of said base, a rear frame mounted on said base and having interlocking engagement with said end members, a front member supported on said base and hav-

ing interlocking engagement with said end members, a removable top inserted in the upper end of the frame formed by the end members and the front and rear frame members, said top frame member having a rectangular opening therein to receive a mechanical refrigerating unit by horizontal movement thereof through the front of the frame.

10 5. A refrigerator, comprising a base mounted on permanently connected supporting legs, a pair of end members mounted one on each end of said base to be supported thereby, a rear frame member resting upon said base and having interlocking connection with said end members, a removable top member inserted in the upper end of the frame formed by the end members and the rear member, said top having a pair of rectangular insulation frames positioned one on each end thereof to leave a rectangular bay between said frames, a flange around the interior of said bay to removably receive and support a mechanical refrigerating unit, by horizontal movement of the unit through the open front of the bay a front closure member removably positioned across the front of said bay, and a removable front frame member supported on a base and having interlocking engagement with said end frame members.

35 6. A refrigerator, comprising a base frame member having a rectangular opening to receive insulation, a pair of end frame members having rectangular openings to receive insulation material mounted on said base frame member to be supported thereby a rear frame member having rectangular openings to receive insulation material and having interlocking engagement with said end frame members, a removable top member inserted in the upper end of the frame formed by the end members and the rear member, said top having a pair of rectangular insulation frames positioned one on each end thereof to
40 leave a rectangular bay between said frames, a flange around the interior of said bay to removably receive and support a mechanical refrigerating unit, by horizontal movement of the unit through the open front
45 of the bay a front closure member removably positioned across the front of said bay, and a removable front frame member having a plurality of door openings therein, said frame member being supported on the base and having interlocking engagement with said end frame members, all of said frame members being adapted to be covered
50 with enameled sheathing material.

55

60 with channeled sheathing material.
In testimony whereof I affix my signature.
GEBHARD C. BOHN.
